INDICATOR RING

James J. Smith, Baltimore, Md.

Application April 29, 1949, Serial No. 90,377

5 Claims. (Cl. 235—106)

1
This invention relates to sequential counting devices and, more particularly, to a registering mechanism adapted to be worn on the person and suitable for use in counting and tallying.

Some religious sects often make use of mechanical counting devices as an aid in the performance of certain forms of devotion. A well-known example of one such devotion is the recitation of the "Rosary" which, most generally, is accomplished with the aid of "rosary beads." However, the numerous prayers in this particular devotion necessitates a chaplet of beads of a relatively large size. Under some circumstances the user may have difficulty in handling this device and may accidentally drop it from his hands. As a result he may lose count of the step or event in his recitation. Accordingly, it would be highly desirable to have, in a readily accessible and convenient location, an easily manipulated indicating device for registering and indicating the various steps or events recited in the "Rosary."

In accordance with this invention there is provided an indicating device readily adaptable for such purposes and capable of being embodied in a finger ring.

A primary object of the present invention is to provide compact and inexpensive apparatus for sequential counting.

A further object is to provide such counting apparatus which is characterized by its simplicity and its durable construction.

A more specific object of the invention is to provide a sequential counting device embodied in a finger ring, permitting the device to be carried in a convenient and readily accessible manner.

Another specific object is to provide a finger ring incorporating an indicating device adapted for counting and indicating the decades of the "Rosary."

Further objects and advantages of this invention will become apparent from the following description taken in conjunction with the accompanying drawings, in which,

Figure 1 is a top plan view of the invention embodied in a finger ring;

Figures 2 and 3 are cross-sectional views taken along the lines 2—2 and 3—3, respectively, of Figure 1; and

Figure 4 is a plan view of one of the components of the invention.

In the drawings similar parts are identified by like numerals.

The invention is herein illustrated and described as a finger ring for counting and indicating the decades of a "Rosary." In this form, the invention will find particular utility as an aid to Rosary recitations, or as an easily carried substitute for a string of rosary beads.

2
Referring now to the drawings, the main body of the finger ring is indicated by the reference numeral 10. The top of the ring band is provided with a circular recess 11 of suitable diameter and depth to accommodate a manually rotatable annular member 12. Member 12 serves as a rotatable dial and, accordingly a number of markings may be inscribed about the periphery of its upper surface 12a. In the present embodiment, these markings include dot 13 and ten (10) other similar and equally-spaced marks 14. Dot 13 represents the beginning (or end) of a counting sequence and marks 14 represent the steps in a "Rosary" decade. Annular dial 12 may be rotated by means of a knurled shoulder portion 15 extending above the main body of ring 10. Any suitable means may be provided for retaining dial 12 in each of its marked positions 13 or 14, however, the drawings show a well-known detent mechanism comprising spring 16 and ball 17 carried in a recess provided in the bottom wall 12b of dial 12. Ball 17 is forced by spring 16 into appropriately spaced indentations 17a in the bottom wall of recess 11. The inner surface 12c of dial 12 carries a pin 18 suitably positioned to engage with, and actuate, the mechanism for registering and indicating the number of revolutions of dial 12 as hereinafter described.

In the embodiment of the invention illustrated each complete revolution of dial 12 corresponds to a "Rosary" decade.

The registering mechanism comprises a cylindrical indicating member 19, shown in greater detail in Figure 4, rotatably mounted in a supporting structure 20. Integral with the latter structure is a circular plate 21 having a diameter that is slightly greater than the inner diameter of dial 12. Preferably, the top of the dial 12a is provided with a seat 22 to accommodate plate 21. For convenience of manufacture support member 20 is cylindrical thereby permitting member 20 and plate 21 to be turned from the same piece of stock. Support member 20 is secured to the ring body 10 by any convenient means such as an axially positioned screw 23. The support member 20, in turn holds dial 12 in recess 11. It should be understood that support structure 20 is fixed to the ring body, however, there may be provided a pin 24 having one end extending into the support member 20 and the other end into a hole in the bottom wall of

recess 11 to prevent rotation thereof when dial 12 is turned. Obviously, support structure 29 may be of shapes other than cylindrical, for example, rectangular, in which case the bottom wall of recess 11 may be provided with an appropriate seat. Screw 23 will then suffice to hold support member 20 in a fixed position.

A cross 25 mounted on plate 21 serves as an index for the above discussed markings 13 and 14. Of course, other forms of index markings may be inscribed on plate 21, or, alternately, at an appropriate location on ring body 16.

As shown in Figure 4, indicating cylinder 19 is provided with an appropriate number of numerals suitably positioned on its circumference at the right hand end. These numerals are so positioned as to appear visible beneath a viewing aperture 26 in plate 21. One end of cylinder 19 is provided with a stub shaft 27, while the opposite end carries a number of circumferentially positioned projections or lugs 28 extending co-axially therefrom. The number of lugs 28 is equal to the number of figures inscribed on cylinder 19. In the illustrated embodiment there are, of course, five of each, corresponding to the number of decades in a "Rosary." Rotatable indicating cylinder 19 is so mounted in its supporting structure 20 that its axis is perpendicular to the axis of annular dial 12, and it is so located that the lowermost of lugs 28 and the actuating pin 18 on dial 12 are positioned in the same horizontal plane. It should be understood that, alternatively, pin 18 could be in the same plane as the highest lug.

The operation of the invention in accordance with the embodiment illustrated and described above is as follows:

With reference to Figure 1 it is seen that a numeral 1 appears in the viewing aperture 26 and that dot 13 is at the foot of the index cross 25. With cylinder 19 and dial 12 so positioned the user knows that he is on the first decade of his prayer. As he completes each part of the first decade he turns dial 12 in a clockwise direction thus first moving the dot 13 away from index marker 25 and placing the first of marks 14 into registry therewith. As the prayers in the decade are recited the corresponding mark 14 is moved away from index 25 and the next successive mark 14 is brought adjacent thereto, the previously mentioned detent mechanism serving to accurately position the dial in each new setting. Upon completion of the tenth and final step in the decade, dial 12 is turned to place the beginning dot in the indexed position. During this particular movement of the dial, actuating pin 18 momentarily engages the lowermost of lugs 28 to turn cylinder 19 through the necessary angle, in this instance seventy-two degrees, to bring numeral 2 beneath viewing aperture 26 and move the next of lugs 28 into its lowermost position. The appearance of numeral 2 through aperture 26 indicates the beginning of the second decade. For each recitation in the second decade, dial 12 is turned step-by-step in the same manner described above for the first decade and, again, movement of dial 12 from the last of the ten equally spaced marks to the decade beginning dot 13 places pin 18 in momentary contact with the lowermost lug to bring numeral 3 on indicating cylinder 19 in view and the next lug in position to be contacted later with pin 18. The same procedure outlined above is followed during the recitation of the remaining decades. Upon completion of the final step in the fifth decade the

movement of dial 12 to set beginning dot 13 in the index cross position replaces numeral 1 beneath aperture 26 thereby conditioning the "rosary ring" for the next "Rosary recitation."

From the above description it will be seen that annular dial 12, with its inwardly protruding pin 18, and cylinder 19, with the co-axially extending lugs 28, cooperate to form an intermittent action type of mechanism for sequential counting procedures, and further that the indices on cylinder 19 register the number of revolutions completed by dial 12, while the markings on the dial indicate the number of incremental movements given thereto. Thus, it is evident that with an appropriately chosen dial 12 and cylinder 19, the number of incremental movements of the dial may be readily determined from the indications given by their positions.

Accordingly, it is to be understood that the present invention is not limited to the specific embodiment and application illustrated and described herein, but, instead, the invention may be employed for other sequential counting procedures.

What is claimed is:

1. In an indicating device, a support member provided with a circular opening extending partially therethrough, an annular indicating member rotatably mounted within said opening, a projection extending inwardly of the inner wall of said annular member, a plate mounting stud secured to the floor of said opening and provided with a circular aperture whose axis is disposed substantially perpendicular to the axis of said circular opening, an indicating member rotatably disposed within said mounting stud aperture provided with a set of characters about its periphery and a driving surface in position for actuation by said projection, and a cover plate provided with a reading window secured to said plate mounting stud with said reading window substantially in register with said character set and retaining said annular member within said circular opening.

2. In an indicating device, a base member, a mounting stud secured to said base member and provided with an aperture extending transversely of said stud, a cylindrical indicating member having a set of characters around one of its peripheries rotatably mounted within said aperture, said cylindrical indicating member also being provided with a drive surface, an apertured cover plate secured to said mounting stud with said cover plate aperture substantially in register with the indicating member periphery bearing said character set, and an annular member surrounding said stud embraced between said base member and said cover plate having an inner projection imparting incremental motion to said drive surface during a portion of the rotation of said annular member.

3. In an indicating device, a base member, a mounting stud secured to said base member and provided with an aperture extending transversely of said stud, a cylindrical indicating member having a set of characters around one of its peripheries rotatably mounted within said aperture, an apertured index bearing cover plate secured to said mounting stud with said cover plate aperture substantially in register with said indicating member periphery bearing said character set, an annular member surrounding said stud embraced between said base member and said cover plate, said annular member having an internal shoulder receiving said cover plate and

a set of graduations disposed on the exposed area adjacent said cover plate, an intermittent incremental drive linking said cylindrical indicating member and said annular member, and a detent mechanism linking said base member and said annular member.

4. A sequential counting mechanism comprising a supporting structure, a rotatable annular dial mounted on said structure, a rotatable cylindrical indicator having a plurality of characters inscribed around the circumference of a portion of its cylindrical surface mounted on said structure within said annular dial and having its axis substantially perpendicular to the axis of the said annular dial, a plurality of circumferentially-positioned lugs extending co-axially from one end of said cylindrical indicator, and an actuating pin protruding radially inward from the inner surface of said annular dial, said lugs and pin being so positioned relative to each other as to permit momentary contact between said pin and successive lugs during successive complete rotations of said dial.

5. The combination with a finger ring, of an indicating device mounted on and forming a component part of the ring, said ring having a recessed upper portion, an indicator element fixed

in said recessed portion, an annular member rotatably seated on the marginal periphery of said recess and having marks representing the order of prayers to be said, and a cylindrical member also arranged in the recessed portion and positioned in a plane normal to the said indicator, said cylindrical member having a plurality of numerals thereon, each of said numerals representing the order of saying a decade of prayers.
